APPARATUS FOR THE CONTROL OF HIGHWAY CROSSING GATES

Paul H. Crago, Wilkinsburg, Pa. Assignor to The Union Switch & Signal Company, Swissvale, Pa., a corporation of Pennsylvania

Application October 28, 1942, Serial No. 463,632

7 Claims. (Cl. 246—130)

My invention relates to apparatus for the control of highway crossing gates, and has particular reference to systems for automatically controlling such gates by railway traffic. More particularly, my invention relates to the provision of novel and improved systems for controlling the operation of highway crossing gates at the intersection of a highway and a multiple track railway.

A control system of the class described involves crossing gates positioned at the intersection of a railway and a highway. These gates are normally held in a vertical or non-obstructing position as long as the approach track section provided for each track is vacant, and are lowered to a horizontal or obstructing position whenever an approach section is entered by a train. The approach sections are each of a length sufficient to assure that the gates will reach their obstructing positions not less than a predetermined interval prior to the time that the head end of the train enters the intersection. Warning devices, such as bells or lights or both, are usually provided at or near the gates and are caused to operate during the time the gates are being lowered, as well as for an interval before the lowering operation is initiated. This operation of the warning devices for a short interval prior to the lowering of the gate arms, provides a preliminary warning period for informing highway traffic that the gates are about to be lowered, and thereby guards against lowering the gates immediately in front of or on top of highway vehicles.

The system also involves operating mechanisms for raising the gates to their vertical positions after each train clears the intersection. This operation requires several seconds to complete, and during this interval a second train might enter an approach section before the gates reach their vertical positions following the passage of the first train. In such an event, it is undesirable to stop operation of the gates and permit them to drop immediately, since highway traffic would then have no warning of the release of the gates and might become trapped on the intersection or struck by the descending arms.

In view of the above-mentioned and other important considerations, an object of my present invention is the provision of apparatus for the control of highway crossing gates incorporating novel and improved means arranged to insure that the movement of a gate to its non-obstructing position will be completed once it has been initiated following the passage of a train.

An additional object of my invention is the provision of novel and improved apparatus for

the control of highway crossing gates arranged to utilize the electric motor of the gate as a dynamic brake when the gate is operating from its non-obstructing to its obstructing position.

- 5 In practicing the invention, the above-mentioned and other important objects and characteristic features which will become readily apparent from the following description, are attained by providing each track with a checking section through which a train must travel to reach the associated approach section, and by providing a control relay with a stick circuit governed by all of the approach sections, and a picked-up circuit governed by all of the approach and checking sections. This control relay governs another relay arranged to be energized in multiple with the gate operating motor and effective in its picked-up position to control the application of energy to the motor and in its released position to apply a snub circuit on the motor. The arrangement is such that the other relay is picked up when a train vacates an approach section provided that all of the approach and checking sections are then vacant.
- 10 25 I shall describe one form of apparatus embodying my invention, and shall then point out the novel features thereof in claims.

The accompanying drawing is a diagrammatic view illustrating one form of apparatus embodying my invention.

- 30 Referring to the drawing, the reference character X designates one track and the reference character Y designates another track of a stretch of multiple track railway. Traffic normally operates over track X in the eastbound direction as indicated by an arrow associated with track X in the drawing, while traffic normally operates on track Y in the opposite or westbound direction as indicated by the associated arrow. The tracks 35 X and Y are divided by insulated joints 2 into a plurality of track sections, designated by the reference characters T with suitably distinguishing prefixes. Each of these sections is provided with a closed circuit track circuit including a track relay designated by the reference character TR with a prefix corresponding to the prefix of the associated section, the association of each relay with its section being indicated conventionally in the drawing by dotted lines. Relays 2TR and 3TR, as indicated in the drawing, form the operating windings of an interlocking relay 2—3TR, while relays 5TR and 6TR form the operating windings of another interlocking relay 5—6TR. These interlocking relays may be of the type disclosed, for example, in Letters Patent of

the United States No. 1,799,629, granted April 7, 1931, to W. K. Lockhart and T. J. O'Meara, and each is characterized by the provision of flagman contacts controlled by a mechanical locking arrangement actuated by the associated armatures in such manner that when either armature is the first to be released, the other armature is then latched up and is prevented from opening its front contacts when subsequently released. Thus, for example, when the armature of relay 2TR is the first to be released, front contact 19 associated therewith opens, and the armature of relay 3TR is latched up so that when the latter relay subsequently becomes released with relay 2TR still released, front contact 20 operated by relay 3TR is held closed.

The stretch of track is intersected at grade by a highway H adjacent to the exit ends of sections 2T and 5T, respectively, hence section 2T may be considered an approach section for railway traffic approaching the intersection on track X in the eastbound direction, that is, from left to right as viewed in the drawing, whereas section 5T may be considered an approach section for westbound traffic approaching the intersection on track Y. Sections 1T and 4T, through which trains operating in the normal direction of traffic on tracks X and Y, respectively, must traverse in order to reach the associated approach sections, will be termed hereinafter checking sections.

The intersection is provided with highway crossing gates G1 and G2 positioned at the intersection on opposite sides of the railway. Each gate has a gate arm biased to a horizontal or obstructing position in which it obstructs highway traffic and an operating mechanism effective to operate the arm to a vertical or non-obstructing position in which the arm clears the highway. For convenience, the horizontal position of the gate arm will be termed the 0° position while the vertical position will be termed the 90° position. The operating mechanisms of the gate are preferably alike and each may comprise any suitable type of signal actuating mechanism, such as, for example, that shown in Letters Patent of the United States No. 1,138,087, granted May 4, 1915, to John P. Coleman. In the application of the patent structure to a crossing gate, it is to be understood that the gate arm is an extended form of the semaphore of the patent. Only the mechanism and controlling apparatus for gate G1 are shown in the drawing for the sake of simplicity since the two gates may be alike and the illustration of the mechanism and control of gate G2 would be but a duplication of that shown for gate G1.

The gate mechanism of gate G1 comprises a motor 10 operatively connected with gate G1 for operating it from its horizontal or 0° position to its vertical or 90° position; a slot magnet 11 having two windings 12 and 13 and effective when the magnet is energized to hold or latch the gate in its 90° position; and a circuit controller J operatively connected with the gate and having contacts selectively closed in accordance with the position of the gate. Associated with the gate mechanism is a snubbing relay SR.

The crossing gate mechanism is controlled by a control relay XR provided with a pick-up circuit which may be traced from one terminal B of a suitable source of current, such as a battery not shown, through front contact 15 of relay 1TR, front contact 16 of relay 4TR, front flagman contacts 17, 18, 19 and 20 of relays 6TR, 5TR, 2TR

and 3TR, respectively, and the winding of relay XR to the other terminal C of the same source of current. Relay XR also is provided with a stick circuit which extends from terminal B through front contact 21 of relay XR, front flagman contacts 17, 18, 19 and 20 of relays 6TR, 5TR, 2TR and 3TR, respectively, and the winding of relay XR to terminal C. Relay XR also is provided with a slow releasing repeater relay XPR energized over an obvious circuit including front contact 22 of relay XR.

The gates are also provided with warning devices, such as a bell 23 and a plurality of lamps 28. The bell 23 is energized over a circuit extending from terminal B through back contact 24 of relay XR, contact 25—26—27 (closed at 3° to 92°) of controller J, and the operating element of bell 23 to terminal C, hence the bell is energized during the preliminary period and while the gate operates from its vertical or 90° position to a position, such as 3°, just short of its horizontal position. The lamps 28 are energized over a circuit having two paths, one including back contact 29 of relay XR and the other including contact 30—31—32 of controller J, hence the lamps are energized whenever relay XR is released or whenever the gate arm is intermediate its 0° and 88° positions. Although only two lamps have been illustrated, it is to be understood that any desired number may be provided, mounted on a pole, gate arm, or wherever desired. Also, the lamp control circuits may be governed by a flasher relay in accordance with the usual practice, but since the particular arrangement incorporating the flasher relay forms no part of my present invention, it has been omitted from the drawing to simplify the description.

In the normal condition of the apparatus, as represented in the drawing, the stretch of track comprising sections 1T to 6T, inclusive, is unoccupied; relay XR is picked up; gate G1 is in its vertical or 90° position; bell 23 and lamps 28 are deenergized; and winding 12 of the slot magnet is energized over a circuit which extends from terminal B through front contact 34 of relay XPR and winding 12 of magnet 11 to terminal C. This winding is the holding winding of magnet 11 and is effective when energized to hold the gate arm latched in its vertical position.

When a train operating over either track in the normal direction of traffic enters either checking section 1T or 4T in approaching the intersection, the track relay of that section releases but the operation of the crossing gates is not initiated until the approach section of that track is entered. For example, if an eastbound train operating on track X enters section 1T, relay 1TR releases to open the previously traced pick-up circuit of relay XR at front contact 15, but relay XR is held energized over its stick circuit including its own front contact 21. When, however, the train enters approach section 2T, relay 2TR releases and its front contact 19 opens to deenergize relay XR. Relay XR accordingly releases and opens its front contact 22 to deenergize relay XPR, but that relay is held up for a slow release interval during which the warning devices 23 and 28 are energized to warn that the gates are about to be released. When relay XPR releases, front contact 34 opens to deenergize winding 12 so that magnet 11 in turn releases to unlatch the gate arm and the arm accordingly begins to move downwardly in response to its bias. Motor 10 operatively connected with the arm is at this time provided with an obvious snubbing

circuit including a resistor 35 and back contact 36 of relay SR. The resistor 35 places a heavy load on motor 10 which now functions as a generator and therefore tends to brake or retard the descent of the arm.

When the arm reaches its 3° position, contact 25—26—27 opens the circuit of bell 23 to end its operation. After the arm drops to its full horizontal or 0° position, it remains there until relay XR picks up. This event occurs when the train vacates approach section 2T, provided that all of the other approach and checking sections are vacant. If, for example, approach section 5T and checking sections 4T and 1T are vacant when the eastbound train vacates section 2T (section 3T of course being occupied), then the closing of flagman contact 19 of relay 2TR, with flagman contact 20 of relay 3TR held closed in its latched position, results in the previously traced pick-up circuit of relay XR being completed and relay XR picks up to close its front contact 21 and thereby complete its stick circuit. In addition, front contact 24 of relay XR closes to complete a circuit extending from terminal B through front contact 24 of relay XR, contact 37—38—39 of controller J and the winding of relay SR to terminal C. Relay SR accordingly picks up to remove the shunt path on motor 10 and to energize that motor over a circuit extending from terminal B through front contact 24 of relay XR, contact 37—38—39 of controller J, front contact 36 of relay SR and motor 10 to terminal C. Also, relay XPR is energized and it in turn energizes winding 12 of magnet 11, but that magnet does not pick up since winding 12 is proportioned to be effective to hold but not to pick up the armature of the magnet. The gate arm is then operated toward its vertical position, and at this time the lamps 28 are energized over their circuits including contact 30—31—32 of controller J, but bell 23 is silent. At the 85° position of the arm, contact 40—41—42 of controller J becomes closed and winding 13 of the slot magnet becomes energized in multiple with winding 12 over a back contact 43 of the slot magnet. When the slot magnet armature is picked up by the cooperative action of the two windings 12 and 13, back contact 43 opens to deenergize winding 13 but the armature is held attracted by its holding winding 12 to maintain the slot magnet conditioned to latch the gate arm in its picked-up position when the gate reaches its 90° position. At the 88° position, contact 30—31—32 of controller J opens to interrupt the circuits for lamps 28 and contact 37—38—39 opens to interrupt the circuits for relay SR and motor 10, whereupon the motor becomes deenergized and relay SR releases to reapply the snubbing circuit path to the motor. The gate then drifts by momentum to substantially its 90° position.

In the event that a second train is in the other approach section 5T or either checking section 1T or 4T at the time that the first train vacates section 2T, relay XR will not pick up because its pick-up circuit will be held open at the front contact of the relay associated with that occupied section. For example, if a following eastbound train enters section 1T before the first train vacates section 2T, then relay 1TR is released and holds open the pick-up circuit of relay XR at front contact 15; and similarly if a westbound train operating on track Y occupies either section 4T or 5T before the first train vacates section 2T, then the pick-up circuit of relay XR

is held open at front contact 16 of relay 4TR or front contact 18 of relay 5TR, as the case may be. In this manner the gate is maintained in its horizontal position by the second train.

5 It is, of course, apparent that the apparatus will operate for westbound trains operating on track Y in substantially the same manner as hereinbefore described for eastbound trains operating on track X, so that further detailed 10 explanation is deemed unnecessary.

The approach sections 2T and 3T are of a length sufficient to insure that the crossing gates will occupy their obstructing positions for a predetermined interval of time prior to the head 15 end of a train entering the intersection. The other two sections 1T and 4T may have any convenient length but each is preferably longer than the distance a train normally covers during the time interval required to raise the crossing gates. These proportions, which may of course be varied, are therefore such as to prevent initiation of the operation of the gates to the raised positions when the first train vacates its approach section should a second train be 20 operating on either track within a distance less than that comprising an approach section and the length of track traveled by the second train in the time interval required for the gates to be operated to the raised position. It follows, therefore, that the gates will be raised to their 25 vertical positions only in the event that conditions are such as will enable the gates to reach their vertical positions before a second train will cause them to drop, whereby there is avoided 30 the possibility of having the operation of the gates to their vertical positions terminated 35 without warning to the highway traffic.

The exit sections 3T and 6T are provided to take care of movements against the direction 40 of traffic on tracks X and Y, respectively, and the relays 3TR and 6TR are arranged so as to release the gates whenever either section is entered by a train operating against the current of traffic on the associated track. The control 45 effected by relays 3TR and 6TR substantially corresponds to that common in practice and will not be described in detail since it forms no part of my present invention.

Although I have herein shown and described 50 only one form of apparatus for the control of highway crossing gates embodying my invention, it is understood that various changes and modifications may be made therein within the scope of the appended claims without departing from the spirit and scope of my invention.

Having thus described my invention, what I claim is:

1. In a highway crossing protective system provided for a stretch of railway track intersected 60 at grade by a highway and provided at such intersection with a highway crossing gate biased to an obstructing position; said gate having an operating mechanism comprising a motor operable to move the gate to a non-obstructing position, a slot magnet operable to hold the gate at its non-obstructing position, and a circuit controller operated by the gate; said stretch of track having associated therewith a normally energized control relay governed by traffic operating over 65 said stretch; said slot magnet having a control circuit including a front contact of said control relay and a contact of said circuit controller closed only in the non-obstructing position of the gate; the combination with the foregoing apparatus of a snubbing relay, a control circuit for

said snubbing relay including a front contact of said control relay and a contact of said circuit controller closed in all positions of the gate except its said non-obstructing position, an operating circuit for said motor including a front contact of said snubbing relay, and a snub circuit connected across said motor through a back contact of said snubbing relay and including a resistance providing a load for the regenerative braking of said motor during movement of said gate from its said non-obstructing to its said obstructing position.

2. In combination with a stretch of railway track intersected at grade by a highway and divided into a first and a second track section traversed in the order named by a train approaching the intersection, a track circuit including a track relay for each of said sections, a highway crossing gate at such intersection having a gate arm biased to an obstructing position, an electric motor operatively connected with said arm for operating said arm from said obstructing to a non-obstructing position, a slot magnet effective when energized to latch said arm in its non-obstructing position, a controller contact operatively connected with said arm and closed in all except the non-obstructing position of said arm, a snubbing relay, a snub circuit including a back contact of said snubbing relay for connecting a resistor across said motor for providing a load for the dynamic braking of said motor, a control relay having a first circuit including its own front contact and a front contact of each of the track relays of said second sections, a second circuit for said control relay including in series a contact of each of the track relays of said first and second sections, a circuit for said slot magnet including a front contact of said control relay, a circuit for said snubbing relay including a front contact of said control relay and said controller contact, and a circuit for said motor including a front contact of said snubbing relay.

3. In combination with a stretch of railway track intersected at grade by a highway and divided into a first and a second track section traversed in the order named by a train approaching the intersection, a track circuit including a track relay for each of said sections, a highway crossing gate at such intersection having a gate arm biased to an obstructing position, an electric motor operatively connected with said arm for operating said arm from said obstructing to a non-obstructing position, a slot magnet effective when energized to latch said arm in its non-obstructing position, a controller contact operatively connected with said arm and closed in all except the non-obstructing position of said arm, a snubbing relay, a snub circuit including a back contact of said snubbing relay for connecting a resistor across said motor for providing a load for the dynamic braking of said motor, a control relay having a first circuit including its own front contact and a front contact of the track relay of said second section, a second circuit for said control relay including in series a contact of each of said track relays, a circuit for said slot magnet including a front contact of said control relay, and means for energizing said snubbing relay in multiple with said motor over a circuit including in series a front contact of said control relay and said controller contact.

4. In combination with a stretch of railway track comprising a plurality of tracks over which traffic normally operates in predetermined directions, each of said tracks being intersected at

grade by a highway and each being divided into a first and a second track section traversed in the order named by trains approaching the intersection in the normal direction of traffic on that track, a track circuit including a track relay for each of said sections, a highway crossing gate at such intersection having a gate arm biased to an obstructing position, an electric motor operatively connected with said arm for operating said arm from said obstructing to a non-obstructing position, a slot magnet effective when energized to latch said arm in its non-obstructing position, a controller contact operatively connected with said arm and closed in all except the non-obstructing position of said arm, a snubbing relay, a snub circuit including a back contact of said snubbing relay for connecting a resistor across said motor for providing a load for the dynamic braking of said motor, a control relay having a first circuit including its own front contact and a front contact of each of the track relays of said first and second sections, a circuit for said slot magnet including a front contact of said control relay, a circuit for said snubbing relay including a front contact of said control relay and said controller contact, and a circuit for said motor including a front contact of said snubbing relay.

5. In combination with a stretch of railway track having a plurality of tracks over each of which traffic normally operates in a predetermined direction, each of said tracks being intersected at grade by a highway and each being divided into a first and a second track section traversed in the order named by trains approaching the intersection in the predetermined direction of traffic for that track, a track circuit including a track relay for each of said sections, a highway crossing gate at such intersection having a gate arm biased to an obstructing position, an electric motor operatively connected with said arm for operating said arm from said obstructing to a non-obstructing position, a slot magnet effective when energized to latch said arm in its non-obstructing position, a controller contact operatively connected with said arm and closed in all except the non-obstructing position of said arm, a snubbing relay, a snub circuit including a back contact of said snubbing relay for connecting a resistor across said motor for providing a load for the dynamic braking of said motor, a control relay having a first circuit including its own front contact and a front contact of each of the track relays of said second sections, a second circuit for said control relay including in series a contact of each of the track relays of said first and second sections, a circuit for said slot magnet including a front contact of said control relay, and means for energizing said snubbing relay in multiple with said motor over a circuit including in series a front contact of said control relay and said controller contact.

6. In combination with a stretch of railway track having a plurality of tracks over each of which traffic normally operates in a predetermined direction, each of said tracks being intersected at grade by a highway and each being divided into a first and a second section traversed in the order named by trains approaching the intersection in the predetermined direction of traffic for that track, a track circuit including a track relay for each of said sections, a highway

crossing gate at said intersection, a control relay, means governed by said control relay for operating said gate, a circuit for said relay including its own front contact and a contact of each of the track relays of said second sections, and a pick-up circuit for said control relay including a contact of each of said track relays of said first and second sections whereby to prevent operation of said gate when any of said first and second sections is occupied.

7. In a highway crossing protective system provided for a stretch of railway track intersected at grade by a highway and provided at such intersection with a highway crossing gate biased to an obstructing position; said gate having an operating mechanism comprising a motor operable to move the gate from its obstructing to a non-obstructing position, a slot magnet operable to latch the gate at its non-obstructing position, a circuit controller operated by the gate, and control means for controlling said gate and hav-

ing a first and a second position; the combination with the foregoing apparatus of a control circuit for said slot magnet including a contact of said control means closed only in its said first position and a contact of said circuit controller closed only in the non-obstructing position of the gate, a relay, an operating circuit for said relay including a contact of said control means closed only in its said first position and a contact of said circuit controller closed in all positions of the gate except its said non-obstructing position, a circuit including a front contact of said relay for connecting said motor to said operating circuit in multiple with said relay, and 15 a snub circuit connected across said motor through a back contact of said relay and including a resistance providing a load for the regenerative braking of said motor during movement of said gate from its said non-obstructing 20 to its said obstructing position.

PAUL H. CRAGO.
